UNITED STATES PATENT OFFICE.

HENRY JANSSEN, OF WYOMISSING, PENNSYLVANIA, ASSIGNOR TO THE
TEXTILE MACHINE WORKS, OF WYOMISSING, PENNSYLVANIA, INCOR-
PORATED.

BRAIDING-MACHINE.

No. 810,056.

Specification of Letters Patent.

Patented Jan. 16, 1908.

Application filed February 18, 1905. Serial No. 246,214.

To all whom it may concern:

Be it known that I, HENRY JANSSEN, a citizen of the United States, residing in Wyomissing, Berks county, Pennsylvania, have invented certain new and useful Improvements in Braiding-Machines, of which the following is a specification.

My invention relates to certain improvements in braiding-machines adapted to produce striped goods by uniting two simultaneously-formed braids at their edges during the process of manufacturing the same, as particularly described in connection with the accompanying drawings and specifically pointed out in the claims.

Figure 1 is a diagrammatic plan view of a portion of a circular-stripe braiding-machine embodying my invention. Fig. 2 is a partial elevation showing the driving-head gearing for one series of carriers. Figs. 3, 4, 5, and 6 are diagrams indicating successive positions of two series of carriers during the formation of two interlocked braids and of the switches, whereby their respective movements with relation to the common driving-head are automatically controlled.

The carrier driving-heads *a*, *b*, and *c* are mounted between the bottom plate *d* and top plate *e* on fixed studs *f*, as usual, and are suitably geared together and to a central drive-gear *g*. Any desired number of intermediate driving-heads *b*, having an even number of carrier-engaging "horns," (four, as shown,) may be employed in a single series in connection with a terminal driving-head *a*, having an odd number of horns, (five,) and a common driving-head *c*, arranged to serve for two coöperating series of driving-heads and their bobbin-carriers by providing the same with double the number of horns that are required for either one of said series, said common driving-head *c* being large enough to so space the horns (six in all, as shown) as to allow the carriers of each series to pass between the carriers of the coöperating series in traversing the common race circle-way *h* of the two series of race circle-ways formed, as usual, in the top plate *e*. The driving-heads are so geared together as to impart to each, as usual, an angular velocity corresponding with the number of horns in each, the common driving-head *c* being driven, however, at a velocity corresponding with a three-horn driving-head, because of

its being adapted to operate as such for each of the two series of braid-forming carriers.

To provide for positively controlling the movement of the carriers of each series through the common race circle-way *h*, as required, to secure the interlocking of the edges of the two sections of braid during their simultaneous fabrication, I employ switches *m* and *n* at the junctions of said common circle-way with the adjoining race circle-ways and switch-operating connections to the driving-head mechanism, whereby alternating carriers of the two series are regularly guided in interlocking passes through said common circle-way and respectively returned to their separate courses, so as to form a close connection of the two braid-sections without possible interference of the carriers and with a uniformly-smooth movement of the latter throughout their prescribed courses. These switches *m* and *n*, as shown, are fixed to vertical shafts *k*, mounted so as to permit of the required oscillating movement. To impart such movement, I provide arms *p* on the shafts *k*, arranged in the path of separate cams *r* on shafts *s*, arranged in gear with the driving-head mechanism, so that said cams are constantly rotated in such relation to the driving-heads as to cause positive shifting of the switches in proper accord with the presentation of the respective carriers at the junction-points of the common race circle-way *h*. The cams *r* are so shaped as to hold each switch in the position to which it is moved thereby during the passage of a carrier, after which a spring *q*, as shown, serves to return and to hold it in reverse position until again operated, as required, by the continued revolution of the cam.

In Figs. 3, 4, 5, and 6 two coöperating eight-carrier series are indicated, the carrier positions in the successive figures being changed in each case by a slight forward movement, as in the normal operation of the machine, the positions of the switches as automatically changed to correspond with the varying positions of the carriers being also indicated. Each carrier is indicated by the same number (1 to 8 in one series and 11 to 18 in the other) in each of the successive positions shown, and the normal direction of movement in the several race-circles and at the switch-controlled junctions is indicated by the arrows. It will be seen that in each

case a carrier arriving at either of said junctions from either direction is positively guided into its own regular course without possible conflict or variation and with uniform smoothness and freedom from undue wear and tear.

To provide for conveniently undoing a portion of the braiding, as for the purpose of correcting a defect in the fabric, I preferably provide a pair of oppositely-arranged switches at each junction, as indicated in the drawings, so as to permit the temporary reversal of the normal movement of the carriers in their regular courses, as required, by merely reversing the movement of the central drive-gear g , as will be readily understood by inspection of the diagrammatic views shown, the cams r being double-acting, or, in other words, arranged to properly operate the switches whether rotated in the normal direction or the reverse.

What I claim is—

1. In a braiding-machine the combination of two series of race circle-ways having a common terminal circle-way, separate series of bobbin-carriers therefor, a common terminal driving-head provided with an odd number of carrier-engaging horns for each series of carriers, means for rotating said driving-head with an angular velocity corresponding with such odd number of horns, a switch at each junction of said common terminal circle-way with an adjoining race circle-way, and a driving-head mechanism having switch-operating connections whereby alternating carriers of the two series are regularly guided in interlocking passes through the common circle-way and returned to their separate courses substantially as set forth.

2. In a Braiding-machine the combination of two series of race circle-ways having a common terminal circle-way, separate series of bobbin-carriers therefor, a common terminal driving-head provided with an odd number of carrier-engaging horns for each series of carriers means for rotating said driving-head with an angular velocity corresponding with such odd number of horns, a pair of oppositely-arranged switches at each junction of said common terminal circle-way with an adjoining race circle-way, and switch-operating cams whereby alternating carriers of the two series are regularly guided in interlocking passes through the common circle-way and respectively returned to their separate courses during either the normal or reverse travel of the carriers substantially as set forth.

3. In a braiding-machine the combination of two series of race circle-ways having a com-

mon terminal circle-way, separate series of bobbin-carriers with driving-heads therefor, a common terminal driving-head provided with an odd number of carrier-engaging horns for each series of carriers means for rotating said driving-heads with an angular velocity corresponding with such odd number of horns, a spring-actuated switch at each junction of said common race circle-way with an adjoining race circle-way and provided with a cam-engaging arm, and a cam for each of said switches arranged in gear with the driving-head and adapted to turn and hold said switches as required to guide alternating carriers of the two series in interlocking passes through the common circle-way and return the several carriers to their separate courses, substantially as set forth.

4. In a braiding-machine the combination of two series of race circle-ways having a common terminal circle-way, separate series of bobbin-carriers therefor, a common terminal driving-head provided with an odd number of carrier-engaging horns for each series of carriers means for rotating said driving-head with an angular velocity corresponding with such odd number of horns, a switch at each junction of said common terminal circle-way with an adjoining race circle-way, and switch-operating mechanism whereby alternating carriers of two series are regularly guided in interlocking passes through the common circle-way and returned to their separate courses substantially as set forth.

5. In a braiding-machine the combination of two series of race circle-ways having a common terminal circle-way, separate series of bobbin-carriers therefor, a common terminal driving-head provided with an odd number of carrier-engaging horns for each series of carriers means for rotating said driving-head with an angular velocity corresponding with such odd number of horns, a pair of oppositely-arranged switches at each junction of said common terminal circle-way with an adjoining race circle-way, and switch-operating cams whereby alternating carriers of the two series are regularly guided in interlocking passes through the common circle-way and respectively returned to their separate courses during either the normal or reverse travel of the carriers substantially as set forth.

In testimony whereof I affix my signature in the presence of two witnesses.

HENRY JANSSEN.
